UNITED STATES PATENT OFFICE.

LEROY CLAWSON, OF HALL, MONTANA, ASSIGNOR OF ONE-HALF TO CHARLES LAVERN
CLAWSON, OF HALL, MONTANA.

AIR-COMPRESSOR.

1,112,054.

Specification of Letters Patent.

Patented Sept. 29, 1914.

Application filed June 23, 1913. Serial No. 775,450.

To all whom it may concern:

Be it known that I, LEROY CLAWSON, a citizen of the United States, residing at Hall, in the county of Granite and State of Montana, have invented certain new and useful Improvements in Air-Compressors, of which the following is a specification.

This invention relates to air compressors, and has for its object to provide a simple 10 and highly efficient mechanism whereby air may be compressed easily and rapidly and fed to a storage tank or reservoir from which it may be carried to the point of use.

The apparatus is adapted for use upon 15 air brakes or other machinery which may be adapted for operation by fluid under pressure.

One object of the invention is to provide 20 means whereby the pressure in the reservoir or storage tank may be automatically relieved when it has reached a predetermined degree without requiring a stoppage of the air compressor.

The invention also has for its object the 25 provision of a simple construction whereby the several parts may be readily assembled and will be held securely in their proper operative relations to the end that the durability and efficiency of the apparatus may be 30 increased, and the invention also seeks to provide novel forms of pistons and a novel valve for controlling the flow of the fluid through the compressor.

These stated objects of the invention, and 35 such other incidental objects as will appear from the following description, are attained in the use of a mechanism such as is illustrated in the accompanying drawings, and the invention consists in certain novel features 40 which will be particularly pointed out in the claims following the description.

In the drawings: Figure 1 is a longitudinal section of an air compressor embodying my invention showing the pistons on the 45 intake stroke; Fig. 2 is a similar view showing the pistons about to complete the compression stroke; Fig. 3 is a transverse section on the line 3-3 of Fig. 1; Fig. 4 is a transverse section on the line 4-4 of Fig. 1. 50 Fig. 5 is a transverse section on the line 5-5 of Fig. 2.

In carrying out my invention, I employ a

bed or base 1 which may be of any convenient construction, and upon the said bed I secure a compound cylinder consisting of a 55 relatively larger intake cylinder 2 and a relatively smaller discharge cylinder 3, the said cylinders being disposed in axial alignment, as clearly shown. The cylinders are preferably cast in one integral body having 60 their meeting ends integral and their outer ends open and provided with annular radial flanges, as clearly shown in Figs. 1 and 2. To the outer end of the larger cylinder 2 I secure, by bolts or equivalent devices, a 65 head 4 having inlet openings 5 therein, and to the outer open end of the cylinder 3, I secure a valve body 6 in a similar manner. Within the cylinders 2 and 3 a piston rod 7 is concentrically disposed and this piston 70 rod and the parts co-acting therewith are assembled within the cylinders before the head 4 and the valve body 6 are secured to the cylinders, as will be readily understood. The piston rod has one end extended through 75 the head 4 and so arranged that the rod may be reciprocated within the cylinders. The rod is smooth on its exterior surface, except as hereinafter described, and its inner extremity is slightly reduced and threaded, 80 as shown at 8.

Upon the threaded extremity 8 of the piston rod is mounted the inner piston consisting of a tubular body 9 which is internally threaded to engage the threaded extremity 85 8 and is provided with an annular flange or disk-like inner extremity which extends radially to and fits closely against the inner surface of the cylinder 3. Through the annular flange or disk-like extremity of this 90 tubular body 9 are formed openings 10 for the passage of the compressed air, as will be hereinafter set forth. A second tubular body 11 is threaded upon the extremity of the piston rod and is turned home against the first- 95 mentioned tubular body 9 and this tubular member 11 is also provided with an annular flange or disk-like extremity indicated at 12 and provided with openings 13 through which the compressed air may escape. After 100 these piston members have been assembled upon the rod the extremity of the rod may be upset so as to retain the piston in position. Between the annular flanges of the

piston members is fitted a cylindrical valve or ring 14, the inner diameter of which is somewhat greater than the outer diameter of the tubular bodies 9 and 11 and the length 5 of which is somewhat less than the distance between the said annular flanges. This ring or annular valve is preferably constructed of two members secured together by rivets 15 for convenience in assembling and also 10 to facilitate the placing or renewing of packing 16 around the valve. The portion of the piston rod which lies within the larger cylinder is constructed with right and left handed threaded portions 17 and 18 upon 15 which are engaged piston members 19 and 20 which are similar in construction to the piston members 9 and 11 and are secured together by rivets or bolts 21. By thus mounting the piston members upon the piston rod through the medium of opposed threads and subsequently securing the piston members together the use of lock nuts is dispensed with and the piston is rigidly secured upon the piston rod. The piston members 19 and 20 are provided with annular flanges or disk-like extremities 22 and 23, respectively, and openings 24 are formed through the said flanges or members, as clearly shown, the openings 24 in the member 19 being disposed near the outer annular edge thereof, while the openings in the member 20 are disposed approximately at the outer surface of the tubular portion of the member. A valve 25 is fitted between 25 the flanges of the piston members 19 and 20 and this valve corresponds in construction to the valve 14, being composed of a two-part ring having its parts secured together by rivets or bolts 26 and carrying an annular packing 27 which bears against the inner surface of the cylinder 2. The inner diameter of this annular valve is somewhat greater than the external diameter of the piston and the length of the valve is somewhat less than the distance between the flanges 22 and 23.

Between the two pistons, I provide around the piston rod means for controlling the flow of the fluid from the cylinder 2 to the cylinder 3 in the form of a peculiarly constructed check valve. This valve consists of two annular bodies 28 and 29 fitted upon the piston rod and having a threaded engagement with each other. The body 28 is provided with 50 an internally threaded ring or annular axial flange 30 at its outer edge, while the body 29 is provided with an externally threaded ring or annular axial flange 31 which is arranged inwardly from the edge of the said body and is adapted to fit within and engage the flange 30 of the body 28. Between the two bodies 28 and 29 a packing 32 is fitted around the piston rod and this packing will be compressed when the member 29 is fitted

to the member 28 so that a frictional engagement with the piston rod will be effected and the valve caused to travel with the piston rod. To insure and maintain this frictional engagement of the packing with the piston rod a compression spring 32' is fitted around the packing and tends to compress the same around the rod. This spring may be of any convenient form and is so tempered and shaped that it tends to contract around the packing and, therefore, automatically compensates for wear upon the packing.

To limit the travel of the valve in one direction a stop ring 33 is secured within the inner end of the larger cylinder 2 by 80 bolts 34 passing through the inner head of said cylinder and the said head presents an internal annular shoulder 35 which will limit the movement of the valve in the opposite direction. The stop ring 33 has an 85 inner diameter somewhat greater than the minimum external diameter of the valve body 28 so that the said body, in the illustrated form, may enter the stop ring in the operation of the apparatus without arresting the flow of the fluid. The maximum diameter of said body, however, is greater than the internal diameter of the stop ring, thereby providing an external annular shoulder 36 which is adapted to abut against 90 the stop ring 33 and arrest the movement of the valve and also, by such action, cut off the flow of fluid between the two cylinders. The valve member 29 is provided with external pins or lugs 37 which are adapted to 95 impinge against the stop shoulder 35 of the cylinders and thereby arrest the movement of the valve toward the cylinder 3 without cutting off the flow of the fluid.

The valve body 6 is secured directly to 105 and against the annular flange at the outer end of the cylinder 3 and contains an internal valve chamber 38 which communicates with the interior of the said cylinder 3. Within this chamber 38 is mounted a 110 valve consisting of a disk 39 having notches 40 in its edge and having a stem 41 extending through the valve chamber to aid in guiding the valve. Around this stem 41 is coiled a spring 42 which tends to normally 115 hold the valve to and against the end of the cylinder 3 so as to prevent the flow of fluid from the cylinder. This position of the valve is illustrated in Fig. 1. When the pressure upon the valve overcomes the tension of the spring 42 the valve will move away from the end of the cylinder, as shown in Fig. 2, and the compressed fluid may then flow through the notches 40 into the valve chamber 6, whence it will escape through a 120 pipe 43 to the reservoir or storage tank. A check valve 44 is preferably fitted in the outlet pipe 43 to prevent back flow of the

fluid. A relief chamber 45 is formed in the valve body 6 beyond the valve chamber 38 and this relief chamber 45 has a vent or outlet 46 opening into the atmosphere. Communication between the valve chamber 38 and the relief chamber 45 is had through small passages 47 formed in the wall separating the two chambers, and flow through these passages is normally cut off by a valve 48 arranged within the chamber 38 and extending over the said openings, as clearly shown. This valve 48 has a valve stem 49 extending through the outer wall of the valve body and having a hollow portion 50 which serves as a guide and support for the end of the valve stem 41. The outer extremity of the valve stem 49 is arranged to bear against one end of a lever 51 which is fulcrumed, as at 52, upon the valve body 20 and has its opposite end pivotally connected to the outer end of a piston rod 53. This piston rod 53 is externally threaded and a presser plate 54 is mounted thereon to bear upon packing 53' which is arranged around 25 the rod and within the cylinder 55 provided therefor. This cylinder 55 is preferably formed within the body 6 and a piston member 56 is carried by the inner end of the piston rod, the packing 53' being confined 30 between said piston member and the presser plate. It will be readily understood that by adjusting the presser plate toward the piston, the packing will be compressed to compensate for wear so that leakage may be 35 prevented throughout the life of the apparatus. The piston is completed by a hollow body 58 which fits around the enlarged head 59 of the piston rod 57 and has an annular flange 60 through which and the member 56 rivets or bolts 61 are inserted to 40 secure the said members together.

The cylinder 55 is open at its outer end and, at its inner end, is in communication with a governor or pressure chamber 62 of 45 less diameter than the cylinder, an annular shoulder 63 being thereby provided against which the flange 60 of the piston member 58 may impinge. A pipe 64 leads from the reservoir or storage tank into the pressure 50 chamber 62 and when the fluid admitted to said chamber reaches a predetermined pressure the piston 56-58 will be forced outwardly, thereby rocking the lever 51 upon its fulcrum and, consequently, forcing the 55 valve 48 away from the passages 47 so that the air driven into the valve body by the compressor will not flow to the tank but will escape into the relief chamber 45 and thence through the vent 46 to the atmosphere. Adjacent the piston 56-58 the piston rod 57 is constructed with an angular portion 65 upon which is mounted a nut or gland 66 adapted to engage the internally 60 threaded wall of the pressure chamber 62.

By rotating the piston rod the gland will 65 be caused to travel upon its threaded engagement with the walls of the pressure chamber and will thereby be drawn inwardly in said chamber so as to compress the packing 67 placed in a stuffing box 68 70 which may be conveniently formed integral with the valve body, as illustrated, and to prevent the gland 66 turning upon and thereby wearing away the said packing, a washer 69 is inserted between the gland and 75 the packing. This arrangement also reduces the resistance to the rotation of the piston rod in adjusting the same.

A spring 70 is coiled around the piston rod 57 and bears at one end against the 80 stuffing box 68 and at its other end against a washer or stop 71 held upon the piston rod by lock nuts 72, as shown. The extremity of the piston rod is made angular, as shown at 73, so that it may be engaged 85 by a wrench or other suitable tool and rotated to assemble and adjust the parts.

It is thought the operation of the apparatus will be understood from the foregoing description, taken in connection with 90 the accompanying drawings. When the piston rod 7 is moved in the direction indicated by the arrow in Fig. 1, the pistons mounted upon the said rod will, of course, move in the same direction and the valve 95 28-29 will move likewise in the same direction until arrested by the shoulder 36 abutting the ring 33. The valve rings 14 and 25, being in frictional engagement with the respective cylinders through the packing in the outer annular surface of said valves, will tend to remain at rest until the annular flanges 12 and 23, respectively, impinge against the valves, whereupon the valves will move with the pistons. This action, however, provides open passages through the front ends of the pistons and between the bodies of the pistons and the valves to the space in rear of each piston, while flow from one cylinder to the other 100 110 115 120 125 cylinder is prevented by the check valve 28-29. A partial vacuum will be established within the larger cylinder between the piston therein and the check valve and, consequently, air or other fluid will flow through the inlet openings 5 and through the passages provided therefor between the piston and the valve carried by the same into the space between said piston and the check valve. At the same time, any fluid which may have been in the smaller cylinder will be compressed between the piston therein and the check valve and will, consequently, be caused to flow through the said piston to the valve 39. Upon the return movement of the piston rod in the direction indicated by the arrow in Fig. 2, the check valve 28-29 will be carried to the

- position shown in said Fig. 2 so that the fluid may flow around the said valve from the cylinder 2 into the cylinder 3. The valves upon the respective pistons will also be caused to fit against the annular flanges 9 and 19 so as to cover the openings 10 and 24, respectively, and, consequently, the fluid will be forced by the said pistons toward the valve 28-29 and the valve 39, respectively. The fluid bearing directly against the valve 39 will be compressed sufficiently to overcome the tension of the spring 42 and said valve will then open to permit the fluid to pass into the pipe 43 and then flow into the reservoir. The nuts 72 upon the piston rod 57 will be adjusted so as to put the spring 70 under a tension corresponding to the pressure it is desired to maintain in the reservoir. So long as the fluid flowing from the reservoir into the pressure chamber 62 is below or just equal to the tension placed upon the spring 70 the governor piston 56-58 and the parts co-acting therewith will remain in the position illustrated. Should the pressure in the reservoir, however, exceed that determined by the tension of the spring 70, the governor piston will be moved outwardly so that the lever 51 will be vibrated and the continued operation of the compressor will then drive the compressed fluid through the vent 46 and not into the reservoir, as previously stated. When the pump is driving the air directly through the relief chamber and the vent 46 into the atmosphere, it will, of course, be working against less resistance than when it is storing the air within the reservoir, and the high temperature of the cylinders due to the compression of the air therein in the ordinary operation of the apparatus will be lowered. As this venting of the machine may occur ordinarily with more or less frequency, the excessive over-heating of the cylinders will be avoided.
- It will be readily noted that I have provided a very compact apparatus by which the air or other fluid may be rapidly compressed to any desired degree and the pressure in the reservoir or storage tank prevented from passing the safety point. The apparatus may be used wherever a supply of compressed air is necessary or desirable and will be found especially advantageous in public garages to maintain a supply of compressed air for quickly inflating the pneumatic tires of automobiles or other vehicles.
- What I claim is:
1. A fluid compressing apparatus comprising axially alined cylinders, pistons working in said cylinders, valves carried by the pistons, a piston rod common to said pistons, a check valve slidably mounted upon a rod between the pistons and in frictional engagement with the rod, and means on the cylinders to limit the movement of the check-valve.
  2. A fluid compressing apparatus comprising axially alined cylinders, pistons working therein and comprising bodies having spaced annular flanges radiating therefrom and provided with fluid passages out of axial alinement, valve rings in frictional engagement with the respective cylinders between said flanges and spaced from the respective bodies, a piston rod connecting said pistons, and a check-valve held frictionally on the rod between the pistons.
  3. In a fluid compressor, axially alined cylinders, pistons working therein, a piston rod connecting said pistons, a valve ring frictionally held upon the piston rod between the pistons and adapted to impinge against the end of the smaller cylinder, and a stop ring secured within the larger cylinder and projecting into the path of movement of said valve.
  4. In a fluid compressor, the combination of a cylinder having an inlet at one end and an outlet at the opposite end, a piston working therein, a valve body secured to and fitting over the outer end of the cylinder, a valve within said body controlling the flow from the cylinder and adapted to close the outlet end thereof, an outlet from said valve body beyond said valve, and a pressure-controlled vent in said body beyond said outlet.
  5. In a fluid compressor, the combination of a cylinder, a piston working therein, a valve body secured to and fitting over the end of the cylinder, said valve body having a relief chamber and a valve chamber, a vent leading from the said relief chamber, an outlet from the valve chamber, a valve within the valve chamber normally closing the end of the cylinder, and pressure-controlled means for establishing communication between the valve chamber and the relief chamber.
  6. In a fluid compressor, the combination of a cylinder, a piston working therein, a valve body secured to and fitting over the end of the cylinder, an outlet from said valve body, a valve mounted in said body and normally closing the end of the cylinder, a pressure chamber within the valve body, an inlet pipe communicating with said chamber, a piston normally closing the said pressure chamber, means controlled by said piston for diverting the fluid from the outlet of the valve body, and means for holding the said piston normally against the pressure within the pressure chamber.
  7. In a fluid compressor, the combination of a cylinder, a piston working therein, a valve body secured to and fitting over the end of the cylinder, means within said body to control the flow from the cylinder, a pres-

sure chamber within the said valve body, an inlet pipe leading into said pressure chamber, a piston rod extending through the said pressure chamber, a piston swiveled on said rod and normally closing the said pressure chamber, a tension device on said piston rod external to said chamber, means within the said chamber for adjusting the said piston

rod, and a vent for the valve body connected with said piston and actuated thereby.

In testimony whereof I affix my signature in presence of two witnesses.
